UNITED STATES PATENT OFFICE

MARION M. HALL, OF PORT NELSON, ONTARIO, CANADA

NECKTIE

Application filed September 9, 1929. Serial No. 391,432.

The principal objects of this invention are to produce a "four-in-hand" tie which will retain its shape under extraordinary conditions and will wear the maximum period 5 and will always present a very excellent appearance.

The principal feature of the invention consists in the novel construction of a lining of bias-cut material and the novel method of 10 securing the lining within the tie whereby smooth, flat folded edges are formed on the lining to engage the interior edged surfaces of the outer tie fabric and whereby the outer fabric is secured throughout its length to 15 the lining in such a manner as to not impair the resiliency of the whole tie.

In the accompanying drawings, Figure 1 is a perspective view of the bias-cut lining prepared ready for securing to the outer covering fabric.

Figure 2 is a perspective view showing the lining and the outer fabric joined together in the novel method of fastening herein provided.

Figure 3 is a perspective detail of a portion of the large end of the tie showing it being reversed to place the lining within the tubular outer covering.

Figure 4 is a cross sectional diagrammatic detail of the finished tie.

It has been proposed to introduce a lining of a bias-cut fabric into the body of "four-in-hand" ties and such lining fabric is preferably woven from wool and has the capability of returning to its natural flat shape after being creased, which is extremely desirable.

According to the present invention, the lining 1 which is formed of a length of bias-cut woolen fabric is shaped to correspond 40 with the shape of the finished tie and its longitudinal edges 2 are folded over to abut approximately centrally of the width of the tie and they are fastened down by a row of zig-zag or diagonal sitches 3 which hold the 45 edges securely but do not hamper the longitudinal stretch or expansion of the fabric.

Woolen fabric such as described is intensely susceptible to the influence of weather conditions and as the folded edges are liable 50 to thicken in damp weather, rows of stitches

4 and 5 similar to the stitches 3 are run along both longitudinal folded-over edges, thus securely holding the two folds of the fabric flat.

The outer or covering fabric 6 is always 55 bias cut and it is folded once along its longitudinal centre line so that the two edges 7 are brought into parallel side by side arrangement, the fabric being folded with the reverse or back side out.

The longitudinal edges 7 are laid over the median line of the lining formed by the abutting edges 2 and a row of zig-zag or diagonal stitches 8 is sewn through the edges of the outer cover and through the lining. The 65 diagonal or zig-zag stitch does not interfere with the stretchable element of the tie.

When the outer covering is thus secured with its raw edges to the centre of the back of the lining, the tie is reversed, turning it inside 70 out in the manner illustrated in Figure 3 so that the lining is placed inside of the reversed outer covering 6.

The doubling of the inside lining prevents 75 curling of the edges of the tie and by stitching it with the zig-zag stitches along the folded edges the edges are held flat. Thus the tie retains a flat neat appearance at all times and does not have a tendency to draw it into tubular or round form through the 80 thickening or distortion of the lining.

The fastening down of the longitudinal abutting edges of the lining prevents their 85 curling, also holds them from overlapping and making the tie too thick and the securing of these longitudinal edges and also the longitudinal edges of the tie to the center line of the lining by means of the zig-zag stitching permits perfect freedom of longitudinal 90 stretch within the limitation of the bias-cut fabric, the threads of the stitch being arranged at substantially the same angle as the threads of the bias cut fabric.

"Four-in-hand" ties are subject to considerable misuse in pulling same around a collar and in knotting the tie and it is important 95 that the outer fabric be prevented from stretching beyond the limitations of the lining as the tie then becomes completely spoiled and by being positively secured to the lining 100

material throughout its entire length by means of a flexible extensible stitch as provided in the zig-zag stitch shown, the outer covering of the tie is held firmly in place.

5 A necktie constructed as described will resist wear very effectively and for the maximum period. It will not readily wrinkle on account of the bias structure of the lining fabric and the peculiarities of the wool threads thereof, nor will it curl at the edges or get out of shape on account of the doubled structure of the lining and the holding stitching described.

What I claim as my invention is:

15 1. A necktie having a lining of bias cut resilient material the longitudinal edge portions of which are folded inwardly with the doubled edges thereof secured flat to the body portion of the lining by zig-zag stitching

20 passing through said edges and body portion, said stitching extending longitudinally thereof and being free of connection with the outer tie material.

25 2. A necktie having a lining of bias cut resilient material the longitudinal edge portions of which are folded inwardly with the marginal fold edges thereof flattened by zig-zag stitching extending longitudinally thereof and free of connection with the outer tie material, said lining being secured to the outer material by a single row of zig-zag stitching extending longitudinally of the finished tie.

30 3. A necktie having a lining of bias cut resilient material, the longitudinal edge portions of which are folded inwardly to overlie the main body portion of the lining with the marginal fold edges thereof flattened by zig-zag stitching extending longitudinally thereof and free of connection with the outer tie

35 material, the inturned raw edges of said lining being disposed centrally and secured flat to the underlying body portion of the lining by a row of zig-zag stitching extending from end to end thereof, said stitching passing through said underlying body portion of the lining and holding said raw edges against undue displacement relative to the latter.

40 4. A necktie having a lining of bias cut resilient material, the longitudinal edge portions of which are folded inwardly to overlie the main body portion of the lining with the marginal fold edges thereof flattened by zig-zag stitching extending longitudinally thereof and free of connection with the outer tie

45 material, the inturned raw edges of said lining being disposed centrally and secured flat to the underlying body portion of the lining by a row of zig-zag stitching extending from end to end thereof, said stitching passing through said underlying body portion of the lining and restricting said raw edges against undue displacement relative to the latter, said lining

being secured to the outer material by a single row of zig-zag stitching which extends longitudinally of the latter row of zig-zag stitching.
